CLAIM

The ornamental design for a photographic diffuser, as shown and described.

DESCRIPTION

FIG. 1 is an isometric view of the photographic diffuser of our design;

FIG. 2 is a top view of the photographic diffuser of FIG. 1; FIG. 3 is a bottom view of the photographic diffuser of FIG. 1;

FIG. 4 is a right side view of the photographic diffuser of FIG. 1;

FIG. 5 is a left side view of the photographic diffuser of FIG. 1;

FIG. 6 is a rear view of the photographic diffuser of FIG. 1; and,

FIG. 7 is a front view of the photographic diffuser of FIG. 1.

The broken lines shown in the drawings depict portions of the photographic diffuser that form no part of the claimed design.

1 Claim, 6 Drawing Sheets
